UNITED STATES PATENT OFFICE.

CHARLES C. HALE, OF WAPAKONETA, OHIO.

TROLLEY-POLE BASE.

932,984.

Specification of Letters Patent. Patented Aug. 31, 1909.

Application filed February 17, 1909. Serial No. 478,431.

To all whom it may concern:

Be it known that I, CHARLES C. HALE, a citizen of the United States, residing at Wapakoneta, in the county of Auglaize and State of Ohio, have invented a new and useful Trolley-Pole Base, of which the following is a specification.

The objects of the invention are, generally, the provision, in a merchantable form, of a device of the class above specified which shall be inexpensive to manufacture, facile in operation and devoid of complicated parts; specifically, the provision of a housing of novel and improved form; of a head designed to be rotatably mounted in the housing; of novel means for maintaining the relation between the head and the housing; and of novel means for protecting the interior of the device against the elements; other and further objects being made manifest hereinafter as the description of the invention progresses.

The invention consists in the novel construction and arrangement of its parts as hereinafter described, delineated in the accompanying drawings, and particularly pointed out in that portion of this instrument wherein patentable novelty is claimed for certain distinctive and peculiar features of the device, it being understood that within the scope of what is hereinafter thus claimed divers changes in the form, proportions, size and minor details of the structure may be made without departing from the spirit or sacrificing any of the advantages of the invention.

Similar numerals of reference are employed to denote corresponding parts throughout the several figures of the drawings.

In the accompanying drawings: Figure 1 shows my invention in vertical transverse section; Fig. 2 is a top plan thereof, parts being broken away better to reveal the structure.

In carrying out my invention, I provide, primarily, a housing, comprising a base plate 1, from which rises a socket 2 circular in outline and inwardly spaced from the periphery of the base plate 1, the said base plate 1 preferably being square in outline. Within the periphery of the socket 2 the base plate 1 carries on its upper face a ball race 3. I further provide a head 4, which is circular in contour and of slightly less diameter than the interior diameter of the socket 2, in or-

der that the edge of said head may not contact with the socket. The head 4 carries upon its lower face a ball race 5 arranged to register with the ball race 3 of the base plate 1; and it is further provided upon its upper face with another ball race, denoted in the drawings by the numeral 6. Rising from the center of the head 4 is a standard 7 having its upper terminal reduced in diameter to form a shoulder 8. I further provide a cap 9, designed to be mounted in the upper terminal of the socket 2. The edge of the cap 9 is threaded, as denoted by the numeral 10, and the socket 2 in its turn is threaded to engage the edge of the cap. The cap 9 is provided with a central aperture 21, designed to receive the standard 7, and about this aperture 21 rises from the cap 9 a flange 11. The cap is provided upon its lower face with a ball race 17, arranged to register with the ball race 6 in the upper face of the head 4, balls 18 being disposed in the several ball races between the cap 9 and the head 4 and between the head 4 and the base plate 1. I further provide a collar 12, arranged to inclose the standard 7, and disposed between said standard 7 and the cap 9, the collar 12 being supported upon shoulder 8 of the standard. The upper terminal of this collar 12 is outwardly turned and downwardly bent to form a flange 13, arranged to inclose the flange 11, which rises from the upper face of the cap. The relation between the flanges 11 and 13 is such that the weight of the collar 12 is carried by the shoulder 8, no part of the same being supported by the cap, and further, the flange 11 of the cap is of such a thickness that it will nowhere contact with the collar 12.

A suitable ear 14 may be arranged to stand from the base plate 1 and the socket 2, the said ear being provided with an aperture 15 to receive the end of an electric wire, the said wire being retained in place by a set screw 16 or like device mounted in the ear 14. As hereinbefore pointed out, the base plate in its preferred form is square, and near each of its corners is disposed an aperture 19 whereby the device may be bolted to the top of a car, the said apertures 19 determining the four corners of a square, so that any side of the base plate 1 may be placed forward. The under face of the cap 9 is beveled upward toward the aperture 21, as denoted by the numeral 20. By this construction a chamber is formed between the

cap 9 and the head 4, and it is designed that this chamber shall be filled with a suitable lubricant to a point approximating the line A—B, of Fig. 1.

5 In practical operation, the cap 9 is rotated downward to hold the balls 18 in place in the several ball races, and it will be seen that when the device is so assembled, the balls serve not only to receive the weight of 10 the structure, which may be carried by the standard 7, but serve as well to receive the lateral thrust of the head 4. By this construction the head 4 is prevented from coming in contact at its edge with the socket 2. 15 The collar 12 serves to protect the interior of the device from the elements and from any dust or dirt which otherwise might find its way thereto. The cap 9 being threaded into the socket 2 is adapted to adjust, to a 20 nicety, the pressure upon the balls 18, and to take up any wear in the balls or the ball races.

It is to be understood that the trolley pole may be mounted upon the upper terminal of 25 the standard 7 in any suitable manner, and it will be seen that when so mounted the same will be anti-frictionally supported and will remain free to turn in any direction under the slightest impulse.

30 Having thus described my invention, what I claim as new, and desire to protect, by Letters Patent, is:—

1. In a device of the class described a 35 housing; a head journaled for rotation in the housing and being provided with a central standard; a cap mounted in the top of the housing and having a central aperture to receive the standard, the cap having a flange upstanding about the central aperture; a collar disposed between the standard and the cap and having a depending flange to inclose the flange of the cap. 40 2. In a device of the class described, a housing; a head journaled for rotation in

the housing and being provided with a central standard, the upper terminal of the standard being reduced to form a shoulder; a cap mounted in the top of the housing and having a central aperture to receive the standard, the cap having a flange upstanding about the central aperture; a collar disposed between the standard and the cap and being supported by the shoulder of the standard, the collar being provided with a depending flange to inclose the flange of the cap. 45 50 55

3. In a device of the class described, a housing having a circular ball race; a head journaled for rotation in the housing and spaced from the sides thereof, the said head being provided with a central standard, the upper terminal of the standard being reduced to form a shoulder, the said head being provided upon its lower face with a ball race registering with the ball race in the housing, 60 and having a ball race upon its upper face; a cap threaded into the top of the housing and being provided with a central aperture to receive the standard, the cap having an upstanding flange disposed about the aperture and having in its lower face a ball race registering with the ball race in the upper face of the head; a collar disposed between the standard and the cap and being supported by the shoulder of the standard, the 65 70 75 collar being provided with a depending flange to inclose the flange of the cap; balls disposed in the races between the cap and the head and between the head and the housing, and being positioned to restrain the head against vertical and lateral movement.

In testimony that I claim the foregoing as my own, I have hereto affixed my signature in the presence of two witnesses.

CHARLES C. HALE.
